MERRY-GO-ROUND

Bobby L. Harness, 5052 Clark Drive,
Shawnee Mission, Kans. 66205

Filed June 22, 1967, Ser. No. 7,557

Term of patent 14 years

(Cl. D34—5)

Fig. 1.

Fig. 2.

Fig. 3.

FIG. 1 is a plan view of a merry-go-round embodying my design;

FIG. 2 is a front elevational view of same; and

FIG. 3 is an elevational view showing same approximately from the side.

The dotted line portions shown in FIGS. 2 and 3 depict conventional vertical axis mountings for purposes of illustration only.

I claim:

The ornamental design for a merry-go-round, as shown and described.
